UNITED STATES PATENT OFFICE.

WILLIAM MORAN, OF SOUTH NORWALK, CONNECTICUT.

VENTILATING-TUNNEL.

SPECIFICATION forming part of Letters Patent No. 714,935, dated December 2, 1902.

Application filed February 13, 1902. Serial No. 93,871. (No model.)

To all whom it may concern:

Be it known that I, WILLIAM MORAN, a citizen of the United States, residing at South Norwalk, county of Fairfield, State of Connecticut, 5 cut, have invented a new and useful Ventilating-Tunnel, of which the following is a specification.

My invention has for its object to provide means for ventilating, more especially removing the smoke and steam of locomotives from, 10 tunnels.

With this end in view my invention consists in the construction substantially as hereinafter described and claimed.

15 In the accompanying drawings, forming part of this specification, I have illustrated one form in which I have carried my invention into effect.

Figure 1 is a cross-section of a tunnel, showing a receiving-pipe in position to receive the smoke and steam from a locomotive and exhaust-pipes on opposite sides thereof; Fig. 2, a horizontal section of the receiving-pipe, the exhaust-pipe, and oblique connecting-pipes 25 looking in the opposite direction from Fig. 1.

A denotes the main portion of the tunnel; B, the receiving-pipe, having a continuous longitudinal slot 10 in its lower side in position to receive smoke and steam as it rises 30 from a locomotive, and C an exhaust-pipe, one or more of which may be used and which may be located above, around, or on either side of the receiving-pipe. The means used for exhausting pipe C forms no portion of my present invention, any suitable exhaust-fan or means for producing a strong air-current being sufficient for the purpose of my invention. In the form illustrated in Fig. 1 the receiving-pipe and exhaust-pipes, on opposite sides

thereof, are shown as supported by brackets 40 11. The connection with the exhaust-pipes is shown as effected by means of oblique forwardly-extending pipes 12.

13 denotes vertical walls in the receiving-pipes, which extend from the edge of slot 10 45 in line with the forward walls of the oblique pipes 12. These walls are used to assist in diverting the smoke and steam into the exhaust-pipes.

In Fig. 1 a locomotive is dotted in front elevation in order to illustrate with perfect clearness the position relative thereto of the receiving-pipe in use. Fig. 2 is a horizontal section, the position being as when a locomotive is moving in the direction of the top of the 55 sheet.

In practice the draft from the exhaust pipe or pipes will draw the smoke and steam into the receiving-pipe and outward into the exhaust-pipes, the walls 13 acting as deflectors 60 and tending to conduct the smoke and steam into the exhaust-pipes.

Having thus described my invention, I claim—

A device of the character described consisting of a receiving-pipe having a continuous slot in its under side, an exhaust-pipe contiguous thereto, pipes leading obliquely forward from the receiving-pipe into the exhaust-pipe, and vertical walls in the receiving-pipe 70 in line with the forward walls of the oblique pipe and extending to the edge of the slot.

In testimony whereof I affix my signature in presence of two witnesses.

WILLIAM MORAN.
